CIRCULATING AND HEATING MEANS FOR BUILDING

Dean L. Thompson, Wichita, Kans.

Application March 31, 1958, Serial No. 725,395

4 Claims. (Cl. 237—1)

This invention relates to buildings. In a more specific aspect this invention relates to dwelling houses and office buildings and to the heating and air circulation thereof. In still a more specific aspect this invention relates to primary and storm windows in and on dwelling houses and office buildings, and to adapting such windows to provide for air circulation and solar heating of the houses and buildings, particularly double-hung primary windows which have a lower portion which raises and an upper portion which lowers. In yet a more specific aspect this invention relates to auxiliary equipment and structure mountable on a building adjacent a double-hung primary window therein, to provide with a usual storm or secondary window for circulating air within a space within the building and heating the air within the building by utilization of solar heat when such is available from rays of the sun.

Double-hung primary windows in dwelling houses and office buildings have been known for a long time and currently exist by the millions, such primary double-hung windows having an upper portion which lowers from the upper portion of the window casing mounting the upper sash, and a lower sash portion which raises from the lower part of the window casing mounting the primary window. Also, it is known to provide such double-hung primary windows with a so-called storm or secondary window, usually and commonly hingedly mounted at the top on the upper part of the window casing to swing outwardly therefrom when desired. Other kinds of secondary or storm windows are known in the art, and the great portion of these can easily be adapted to swing outwardly from the building and window casing upon hingedly mounting same at the top. These storm windows are utilized to provide a double seal against cold air from the outside entering the building in undesired quantities, and to provide an insulating dead air space between the storm window and double-hung primary window. They do not add to the heat in the building, but do keep heat from escaping through the windows. Throughout the year, and particularly in the winter months in the Northern Hemisphere, when the sun is nearer the horizon, a great deal of solar heat is available if it can be recovered and used, that is, radiant heat. The new heating means of my invention for a building effectively recovers and utilizes this available solar heat. Further, the new means of my invention results in air circulation within the building, which is of great advantage, since it provides for an even heating and eliminates stratification of air within the building. The new air circulating and heating means of my invention is particularly advantageously employed in cooperative combination with a common and usual double-hung window which has an upper sash and pane which lowers from the top and a lower sash and pane which raises from the bottom, and a usual and common storm window hingedly mounted to the window casing of the building at the top

2

to swing outwardly from the building, or a storm or secondary window which is converted to do so.

The heating and ventilating means of my invention is for use on a building which has a window with an upper portion which lowers and a lower portion which raises. The combination employs an outer window, preferably the so-called storm or secondary window which is hingedly mounted at its top on the building or window casing. Side members are constructed and mounted on the building, usually the window casing, and they fit between the building and the outer window, such outer window projecting outwardly and downwardly from the upper portion of the primary window. A lower or bottom enclosure member is mounted on the window casing or building, and this lower member fits between the building and the outer window in its lower portion. This lower or bottom member on its upper side has solar heat absorbing means, preferably finned metal members finished a dark shade. These solar heat absorbing means are heated when rays from the sun shine thereon, such rays passing through the outer or storm window. In operation the heating and air circulating means of my invention passes air out from the building under the lower sash of the window when it is in a raised position, heats this air in contact with the heat absorbing means which has been heated by rays of the sun shining thereon, passes the resulting heated air upwardly between the outer window and the prime window and back into the building over the top of the upper window portion of the primary window when it is in a lowered position.

It is an object of my invention to provide new heating and circulating means for buildings, particularly dwelling houses and office buildings.

It is another object of my invention to provide new means for recovering and using solar heat to heat dwelling houses and office buildings, or other types of buildings.

Yet another object of my invention is to provide new structural means to adapt a double-hung primary window and storm window therewith for recovering and using solar heat.

Still another object of this invention is to provide new heating and air circulating means for more economically and efficiently heating buildings, particularly dwelling houses and office buildings, such heating and circulating means providing for circulating air within the building to give an even heat condition as well as utilizing solar heat without any operating expense.

Other objects and advantages of the new air circulating and heating means for a building of my invention will become apparent to those skilled in the art upon reading this disclosure.

Drawings accompany and are a part of my disclosure. These drawings depict preferred specific embodiments of the new air circulating and heating means for a building of my invention, and it is to be understood that the drawings are not to unduly limit the scope of my invention.

In the drawings, Fig. 1 is a perspective view of a preferred specific embodiment of the new air circulating and heating means for a building of my invention, such being mounted and assembled in operating position on the building, and utilizing a common and usual storm window with a usual and common double-hung primary window.

Fig. 2 is a perspective view of the air circulating and heating means of Fig. 1 with the auxiliary side and bottom structure disengaged and the storm window swung inwardly in or against the window casing.

Fig. 3 is an enlarged longitudinal cross sectional elevation view of the air circulating and heating means of my invention shown in Figs. 1 and 2, and showing in

dotted lines the position of the bottom member when swung downwardly and in against the building.

Fig. 4 is a cross sectional plan view showing a portion of the window casing, a side member, and the outer storm window, and showing preferred means to engage the storm window with the side members.

Fig. 5 is a partial longitudinal cross sectional elevation view through a preferred specific embodiment of the new air circulating and heating means of my invention as adapted to a building having a brick veneer structure and a double-hung window.

Fig. 6 is a cross sectional plan view showing a portion of the window casing, brick veneer, side member, and outer storm window of the preferred specific embodiment of Fig. 5, and showing preferred means for engaging the side members and the storm window.

In Figs. 4 and 6 in dotted lines is shown the position of the side members when swung backwardly against the building or window casing.

Following is a discussion and description of the new heating and air circulating means of my invention made with reference to the drawings whereon the same reference numerals are used to indicate the same parts or structure. The discussion and description are of preferred specific embodiments of the new heating and air circulating means of my invention for a building, and it is to be understood that such discussion and description are not to unduly limit the scope of my invention.

Referring now to the drawings, the preferred specific embodiment of the new heating and air circulating means of my invention is shown in relation to a primary double-hung window mounted in a building 8 in one of the sides thereof. The double-hung window has an upper sash 10 and pane 12 therein, and lower sash 14 and pane 16 therein. The sash 10 is mounted in a window casing having an upper portion 18, side portions 20, and a lower portion or sill 22. Likewise, lower sash 14 is mounted in this window casing. Sash 19 lowers to provide for an opening between the upper part of the sash and portion 18 of the window casing, and lower sash 14 raises to provide an opening into the space within building 8 between the lower portion of sash 14 and sill 22 of the window casing. Sashes 10 and 14 and window panes 12 and 16 therefore, respectively, and the window casing having top 18, sides 20 and sill 22 are the usual and common variety used extensively throughout the world, and preferably made of wood or metal with transparent glass panes 12 and 16 normally. The building 8 shown in the drawings Figs. 1 through 4 is of the common wood siding structure.

A common and usual storm window 25 having an upper transparent pane 27 and a lower transparent pane 29, usually of glass, is hingedly mounted by its upper rail 31 and hinges 33 to the top portion of window casing 18. The storm window 25 is hinged to swing outwardly to the position shown in Figs. 1 and 3, or when swung inwardly to fit the window casing to serve as an ordinary storm window (Fig. 2).

A pair of side members 36 of preferably triangular shape (as shown) are hingedly mounted on side portions 20 of the window casing, such mounting being in mirror image relation and so that the side members 36 can lie back against building 8 (Fig. 2), or so they can be projected outwardly from the building 8 (Figs. 1 and 2), to engage the side rails 39 of storm window 25 to position the storm window at an angle with the primary window and building 8, and so that storm window 25 projects outwardly and downwardly from the upper portion of the primary window and top portion 18 of the window casing. Side members 36 preferably have an inwardly turned outer edge 40 which engages clamp means 43 on the inner side of rail 39 of storm window 25, such clamps when tightened over edge 40 holding side members 36 and storm window 25 rigidly engaged in the position of Figs. 1 and 3. The side members 36 are suitably mounted hingedly on casing 20 portions, such as in the manner

shown in Fig. 4 of the drawings. Side members 36 can be constructed of any suitable material and can be of glass or plastic to be transparent, if desired, particularly where it is desirable to utilize the sun's rays in the morning and evening for heating purposes, as set forth herein-after.

A lower or bottom member 46 is suitably hingedly mounted on window sill 22 of the window casing, so that bottom member 46 can lie down against building 8 (Figs. 2 and 3, dotted lines), and so that bottom member 36 can be projected outwardly to engage lower rail 49 of storm window 25 when storm window 25 is swung outwardly (Figs. 1 and 3). Bottom member 46 preferably has an outer panel of a sash 51 and pane 53 which is hingedly mounted to portion 55 in any suitable manner. This particular sectional structure construction of bottom member 46 has been found very advantageous in providing for efficient recovery of solar heat passing through transparent pane 53 of the panel radiantly. A portion 55 of bottom member 46 is insulated by a suitable insulating material 57 between the preferably metal upper plate 59 and lower plate 61 of bottom member 46. Hook and eye means 63 are preferably employed to rigidly join bottom member 46 to the bottom rail 49 of storm window 25. See Figs. 1 and 3 of the drawings. When bottom member 46 is pivoted down against building 8, for example in the summer months, I find it advantageous to pivot outer sash portion 51 back up between inner portion 55 of bottom member 46 and building 8. See Figs. 2 and 3 of the drawings. This has been found to protect window pane 53 from breakage. A hook 65 attached to the outer edge of inner portion 55 of bottom 46 hooks in an eye 67 in building 8 when bottom member 46 is pivoted back against building 8. A plurality of spaced and parallel heat absorbing fins 69 are preferably rigidly secured to top plate 59 of inner portion 55 of bottom 46. These fins 69 are preferably made of metal and colored a dark color to absorb radiant heat from the sun's rays passing through transparent panes 27, 29, and 53 of storm window 25 and sash 51, respectively.

In Figs. 5 and 6, building 8 has a brick veneer 72 thereon. Bottom or lower member 46 having heat absorbing means for solar heat thereon is made in three sections, namely the outer sash and pane section (not shown) which engages the storm window, and two substantially horizontally disposed sections 75 and 77 which are preferably suitably insulated with insulation material 57. Sections 75 and 77 are suitably hingedly connected together to provide for section 75 being turned down against the face of brick veneer 72 when the heating and ventilating structure is in the position of Fig. 2. This sectional construction is made necessary by the additional projection of building 8 resulting from brick veneering same. Likewise, side members 36 (Fig. 6) are made in sections, namely an outer portion 80 and an inner portion 82 which are hinged together. This provides for turning outer portion 80 back against the face of brick veneer 72 when the assembly is in the position of Fig. 2 of the drawings. Again, this sectional construction of side members 36 is necessitated by the additional projection of building 8 due to brick veneering same with brick 72.

In use, the new heating and air circulating means of my invention is shown in proper position in Figs. 1 and 3. With rays from the sun striking heat absorbing means 69 to heat same, cool air from the space or room within building 8 passes under sash 14 of the primary window and out into the space between storm window 25 and the primary window, and further defined by side members 36 and bottom member 46. The air in contact with heat absorbing means 66 is heated. Upon being heated, this air rises upwardly in the passageway created by the assembly, and thus between storm window 25 and the primary window, and ultimately passes back into the space or room within building 8 over the top of upper

sash 10 of the primary window between same and portion 18 of the window casing. Thus, air within building 8 is heated, and the air within the building is constantly circulated to give even heat and to overcome stratification of air within building 8.

The side members 36 and bottom members 46 and 51 and 53 can conveniently be pivoted back against the building 8 during periods of non-use, for instance in the summer months, or they can be removed from the building completely, if desired, with or without secondary and storm window 25.

As will be evident to those skilled in the art, various modifications of the new heating and circulating means for a building of my invention, can be made, or followed, in the light of this disclosure and discussion, without departing from the spirit or the scope of the disclosure, or from the scope of the claims.

I claim:

1. Air circulating and heating means for a building having a primary window with an upper portion which lowers and a lower portion which raises, comprising, in combination, a storm window having a lower transparent portion and hingedly mountable in its upper portion on said building to swing outwardly from said first-named window and constructed when swung inwardly to provide a secondary or storm window therefor, spaced side members hingedly mountable on said building and constructed to be projectable outwardly therefrom when mounted to engage said storm window to position same at an angle with said primary window, means to hold said storm window and side members in engaged position, a bottom member hingedly mountable on said building and constructed to be projectable outwardly therefrom to engage said side members in the lower portion when said side members are mounted and swung outwardly from said primary window, means to hold said bottom member and side members in engaged position, and solar heat absorbing means on said bottom member other than that inherent with window structures, said heating and circulating means adapted when mounted to pass air from said building under said lower window portion when in a raised position, heat said air when rays from the sun are directed on said heat absorbing means, pass resulting heated air upwardly between said storm window and said primary window and over said upper window portion when in a lowered position and thus back into said building.

2. Air circulating and heating means for a building having a window with an upper portion which lowers and a lower portion which raises, comprising, in combination, an outer window having a lower transparent portion and mountable in its upper portion on said building to swing outwardly therefrom, spaced side members mountable on said building to be projectable outwardly therefrom to engage said outer window when same is mounted and swung outwardly from said building, means to hold said outer window and side members in engaged position, a bottom member mountable on said building and constructed to be projectable outwardly therefrom to engage said side members when same are mounted and swung outwardly from said building, means to hold said bottom member and side members in engaged position, and solar heat absorbing means with said bottom member other than that inherent with window structures, said heating and circulating means adapted when mounted to pass air from said building under said lower window portion, heat said air when rays from the sun are directed on said heat absorbing means, pass resulting heated air upwardly between said outer window and said first-named window and over said upper window portion

when in a lowered position and thus back into said building.

3. Air circulating and heating means for a building having a window with an upper portion which lowers and a lower which raises, comprising, in combination, an outer window mountable on said building, side members constructed and mountable on said building to fit between said building and said outer window when said outer window is mounted projecting outwardly and downwardly from the upper portion of said first-named window, a lower member having solar heat absorbing means other than that inherent with window structures and mountable on said building and constructed to close the space between said building, side members and said outer window in their lower portions, when such are mounted and projecting said heating and circulating means adapted when mounted to pass air from said building under said lower window portion when in a raised position, heat said air when rays from the sun are directed on said heat absorbing means, pass resulting heated air upwardly between said outer window and said first-named window and into said building over the upper portion of said upper window portion when in lowered position.

4. Air circulating and heating means for a building having a window casing and therein a double-hung primary window with an upper sash and pane which lowers and a lower sash and pane which raises comprising in combination, a transparent storm window hingedly mountable in its upper portion on the outer upper portion of said window casing to swing outwardly therefrom and constructed to fit said window casing when swung inwardly to serve as a usual secondary or storm window, a pair of triangular-shaped and imperforate side members hingedly mountable in mirror image relation on the outer portions of the sides of said window casing to lie back against said building and to be projectable outwardly therefrom to engage said storm window along its sides when mounted and swung outwardly to position said storm window at an angle with said primary window, means to hold said storm window and side members in engaged position, an imperforate bottom member having outer plates and insulation therebetween and hingedly mountable on the outer portion of the bottom of said window casing to lie down against said building and to be projectable outwardly therefrom to engage said side members when mounted and swung outwardly, a sash and pane hingedly connected to said bottom member and engageable with the bottom of said storm window when mounted and swung outwardly, means to hold said bottom member and side members in engaged position, means to hold said last-named sash and pane in engaged position with said storm window, and a plurality of spaced and parallel metal solar heat absorbing members mounted on the upper plate of said bottom member and projecting therefrom, said heating and circulating means adapted when mounted to pass air from said building under said first-named lower sash and pane when in a raised position, heat said air when rays from the sun are directed on said heat absorbing members, pass resulting heated air upwardly between said storm window and said primary window and over said upper sash and pane when in a lowered position and thus back into said building.
